(57) **CLAIM**

The ornamental design for a protective glove, as shown and described.

DESCRIPTION

FIG. 1 is an isometric view of a protective glove showing our new design.

FIG. 2 is a rear elevation view thereof.

FIG. 3 is a front elevation view thereof.

FIG. 4 is a left side elevation view thereof.

FIG. 5 is a right side elevation view thereof.

FIG. 6 is a top plan view thereof; and,

FIG. 7 is a top plan view thereof.

The darker areas on the tips of the thumb and finger stalls illustrate a contrast in appearance.

The broken lines in the drawings illustrate environmental subject matter and form no part of the claimed design.
